UNITED STATES PATENT OFFICE.

LEWIS PERRY, OF NEW YORK, N. Y.

DESIGN FOR A CANDY BOX.

Application filed November 14, 1925. Serial No. 15,418. Term of patent 7 years.

To all whom it may concern:

Be it known that LEWIS PERRY, a citizen of the Republic of Greece, residing at No. 118 West 72nd Street, New York city, New York, has invented a new, original, and ornamental Design for a Candy Box, of which the following is a specification, reference being had to the accompanying drawing, forming a part thereof.

The figure shown is a perspective view of said candy box showing my new design.

I claim:

The ornamental design for a candy box as shown.

In testimony whereof, I have hereunto affixed my hand this 26th day of October, 1925.

LEWIS PERRY.
